UNITED STATES PATENT OFFICE.

JOHN THOMSON, OF BROOKLYN, NEW YORK.

ELECTRIC FURNACE.

1,351,977.

Specification of Letters Patent.

Patented Sept. 7, 1920.

Application filed November 10, 1919. Serial No. 339,119.

To all whom it may concern:

Be it known that I, JOHN THOMSON, a citizen of the United States, and a resident of borough of Brooklyn, county of 5 Kings, State of New York, have invented new and useful Improvements in Electric Furnaces, of which the following is a specification.

This is an invention in electric furnaces 10 and is here illustrated as adapted for fusing metals. Its thermal element is of the monolithic, zig-zag, resistance type, usually formed of graphitized carbon.

Among the objects hereof, the following 15 are dominant:

To situate and arrange the limbs of a compound, zig-zag resistor and its terminals in such manner that the limbs of the resistor may be operated separately, or both 20 in series, or both in parallel;

To so dispose the resistor along the side, or sides, of a receptacle for containing the material to be heated that essentially all of the heat-rays, upwardly radiated therefrom 25 in parallel, shall thereafter be downwardly refracted in parallel;

To provide a sectional cover, capable of being partially removed from the furnace-chamber; and

30 To provide a door, for closing the charging-port in a wall of the furnace, whose inner heated surface shall be parallel with the inner, contiguous vertical surface of the furnace.

35 In the accompanying drawings,—

Figure 1 is an end elevation of the furnace in which the charging-port door is shown open;

Fig. 2 is a vertical, transverse center section, viewed toward the charging-port;

Fig. 3 is a vertical, longitudinal center section;

Fig. 4 is a plan view, the cover of the furnace being omitted;

45 Fig. 5 is an enlarged sectional diagram, transversal to a limb of the resistor; and

Fig. 6 is a semi-diagrammatic transverse section showing a modification in the construction of the furnace.

50 The thermal element is generally known as a compound zig-zag resistor, that is such a unit, in singular, is formed by two monolithic carbon limbs, one pair of ends having hitherto been joined to operate in series, by 55 a carbon connector, wholly contained with-

in the furnace-chamber, the alternate ends being connected to carbon terminals which pass out through a wall, or walls, of the furnace.

In the present case the monolithic limbs 60 B, C, of the resistor are detachably connected to carbon terminals D, E, and F, G, (see Fig. 4) which pass out from the furnace-chamber H through opposite side-walls of the furnace. In this wise, either of 65 the limbs may be operated as a distinct elemental resistor, or both may be operated in parallel; but by joining a pair of the terminals, as F, G, with a copper connector I, on the exterior of the furnace, the two limbs 70 are operative in series. Hence, if it should become desirable, for any reason, to change from series to parallel this can be effected by simply disconnecting the connector; or, should one or the other of the limbs fail, 75 the alternate limb can be operated as an integral unit, whereby a partially fused charge can be fluidified instead of being "frozen," as might otherwise be the case.

The limbs of the resistor are disposed, 80 right and left, along the sides of a charge-receptacle J in which a molten bath is denoted by J', and rest upon refractory bases K, K' (see Figs. 2 and 5) transversely sloped downwardly from the horizontal, 85 longitudinal center of the furnace-chamber. In the drawings, the angles of these bases are about 30°; which, however, may be lesser or greater, depending upon the co-ordinating conditions to be realized. 90

The monolithic limbs of the resistor are here shown as being embedded, or covered, with granular carbon L which may be more or less consumed if air is present but serves to prevent the oxidization of the resistor 95 itself. Between the granular carbon and the monolithic resistor, there may be a layer of material M (see Fig. 5) relatively non-conductive to electricity. Consequently, heat is developed solely by the monolithic 100 resistor; is transferred by conduction to the broken carbon and is then radiated in parallel rays vertical to the emitting surface, as indicated by the arrows a, b. The heat thus radiated is then refracted by the inner surface N of the cover in correspondingly parallel rays, as is indicated by the arrows d, e, and impinge upon the surface of the bath or object to be heated. To express the problem in concrete terms, the requisite condi- 105 110

tions, whereby to realize the foregoing desirable effect, are that the relatively flat heat-emitting face of the resistor or of the granular carbon, and the flat heat-refracting face of the cover shall be disposed at such a relative angle as will "throw" the heat-rays in parallel to the desired surface of impact.

It follows, therefore, that the area of the heat-emitting surface acted upon by the resistor may be equal to, or lesser than, or greater than, the heat-absorbing surface of the charge; also that the deflection of the radiated heat-rays may be controllably realized by disposing the resistor along a horizontal plane and obtaining the desired deflecting angle from the cover, as is illustrated in Fig. 6, in which the resistor-limbs are laid horizontally while the roof is sloped upwardly from the horizontal, right and left, toward the center. The roof-angles here shown are about 25° . Moreover, in this illustration the heat-emitting surface is shown as having about twice the area of the bath, whence the parallel heat-rays from each limb of the resistor have approximately common points of impingement. Obviously, in a case where it is desirable to deliver the greatest possible volume of heat at a given temperature this realization of the invention would be the better.

It will now be perceived that approximately every portion of the entire surface of the bath, J' , is subjected to refracted heat-units traversing nearly uniform distances; and that the dynamic effect thereof will only be so much less than that of the radiated heat a, b as is measurable by the energy necessary to cause the downward deflection. The practical advantages of the foregoing are the avoidance of "hot-spots" at, or in, any portion of the bath or article to be heated; consequently the potential difference of temperature between the source and the delivery is uniformly distributed and heat-units may be supplied as rapidly as they can be absorbed.

When the conditions are such that oxidation will not ensue, a monolithic zig-zag carbon resistor may be used without being embedded in crushed carbon.

I have previously disclosed how controlled heat-refractions from portions of a monolithic resistor may be realized from the side-walls of electric furnaces as, for example, in my Patents No. 1,308,877 and No. 1,308,880 of July 8, 1919.

But if a monolithic resistor is disposed, as shown in the drawings, and enveloping carbon is used it is desirable that the latter, when more or less consumed, may be conveniently renewed; also that either or both of the resistor-limbs, if impaired or damaged, may be replaced.

Incidentally, an arched cover would not

so effectively meet the desired thermal conditions herein set forth, in that the heat-rays refracted therefrom would be converged toward its center; moreover, there would then be a more considerable difference in the lineal distances traversed by the heat-rays refracted from the arch to the charge; the cubical capacity of the furnace-chamber would need be greater and removal of the entire cover would then be required in order to reach the resistor. On the other hand, the construction of a flat cover for furnaces of large capacity present considerable difficulties in that monolithic refractories which will enduringly span wide chambers, when subjected to high temperatures, are limited and expensive. This problem has been successfully solved, by the employment of ordinary tiles or bricks in the following manner:

The cover or roof, in singular, is preferably formed in three sections Y, Y', Y'' abutting along the lines m, n , whereby either or both of the outer sections may be partially slid to one side, thereby wholly exposing each limb of the resistor, when consumed, crushed carbon may be conveniently renewed; or, if required, the monolithic resistor can be removed and replaced. The tiles or bricks are pierced as r (see Fig. 2) assembled to produce a section and upon the top thereof is a layer of heat-insulating blocks. Iron pipes, V , are introduced through the tile-holes and corresponding pipes, or in this place solid rods, overlie the said insulating blocks. Iron clamps, as P , are engaged by the pipes whose ends are threaded and the structure is then very firmly bound together by nuts, as t . Each pair of pipes, or a pipe and a rod, one being superimposed above the other, form a very strong and rigid structure, analogous to a bridge-member; consequently the sections may be swung off without liability of deformation. If the pipes become so highly heated as to produce plasticity, this can be corrected by circulating therethrough air or water. Obviously a so-called "flat arch" could be employed but it also would usually require to be clamped together and its wedge-blocks would be more expensive to construct and less adaptive to various sizes of furnaces. Another advantage of being able to use ordinary tiles, with parallel surfaces, resides in the fact that standard carbonaceous forms may be employed. An important advantage of constructing the cover in sections is that but one portion need be slid over at a time; and, as it rests upon the top of the furnace-wall, its hot inner surface is not exposed to atmosphere.

The charging port, R , is normally closed by a "door," S , formed of suitable refractory material, in the top of which is a hook, as v , to which a chain may be attached (not

shown) passing upwardly over a pulley and thence downwardly, whereby the said door can be elevated, as shown in Fig. 1, or lowered, as shown in Fig. 3. This door is freely fitted within a gap or recess T so that its inner surface is brought approximately parallel with the contiguous, inner, vertical surface of the chamber wall. Hence a pernicious heat-absorbing pocket, which would exist if the door were disposed outwardly, is avoided; also, when elevated, its hot, inner surface slides upwardly in contact with heated brickwork, instead of, as is usually the case, being exposed to a cold surface and atmosphere. Incidentally, this disposal and mode of operation is very convenient in that the open door is not in the way of an operator and the maximum of accessibility to the port and the furnace-chamber is afforded.

Obviously various changes may be made in the details of construction and arrangement of ports herein illustrated and described, within the purview of this invention.

What I claim is:

1. An electric furnace provided with a compound, monolithic, zig-zag, carbon resistor formed of two limbs, the ends of each limb being connected to carbon terminals which pass out from the heating chamber to the exterior of the furnace, and a metallic connector, outside of the furnace-chamber, attached to one terminal of each of said pair of terminals, whereby the limbs of said resistor may be electrically incited to series.

2. An electric furnace provided with a compound, monolithic, zig-zag, carbon resistor formed of two limbs, the ends of each limb being connected to carbon terminals which pass out from the heating chamber to the exterior of the furnace, whereby the said terminals may be so connected, outside of the furnace-chamber, as to electrically incite both of said limbs in parallel or either thereof in series.

3. An electric furnace provided with a compound zig-zag carbon resistor whose limbs are disposed along the opposing sides of a charge-receptacle, said limbs being connected to suitable terminals, and an overlying cover for the furnace from which the heat-rays upwardly radiated in parallel by

the said resistor are downwardly reflected in parallel to the object to be heated.

55

4. An electric furnace provided with a zig-zag carbon resistor, connected to suitable terminals, disposed along the side of a charge-receptacle, said resistor being set at an angle, transversely, and an over-lying flat cover for the furnace whereby the heat-rays radiated from the resistor in parallel are refracted in parallel from the cover to the object to be heated.

60

5. An electric furnace provided with a zig-zag carbon resistor, connected to suitable terminals disposed along the side of a charge-receptacle, said resistor being set horizontally and an overlying cover for the furnace having a flat surface set at an angle transversely from the horizontal, whereby the heat-rays radiated from the resistor in parallel are refracted from the cover in parallel to the object to be heated.

70

6. An electric furnace provided with a monolithic zig-zag carbon resistor connected to suitable terminals disposed along the side, or sides, of a charge-receptacle, said resistor being embedded in or covered by crushed carbon, and an over-lying sectional roof for the furnace whose arrangement and construction are such that one or more of its sections may be partially slid off side-wise from the furnace-chamber exposing the resistor whereby either the said crushed carbon or the monolithic resistor may be intermittently renewed or replaced.

80

7. In an electric furnace provided with a charge-receptacle and a resistor disposed along the opposing sides of said receptacle whose radiated heat passes upwardly in parallel, a cover comprised in a plurality of separable sections whose inner surfaces are flat or sloped from the horizontal, each section being formed from rectangular refractory tiles compressed together by metallic tubes, the latter passing through the said tiles and capable of being cooled by air or water.

85

This specification signed this 15th day of November, A. D., 1919.

JOHN THOMSON.
